METHOD OF PRODUCING WAIST BAND CURTAINS

Filed June 24, 1929

UNITED STATES PATENT OFFICE

OLIVE K. THOMAS AND JOSEPH D. MALKIN, OF PHILADELPHIA, PENNSYLVANIA, ASSIGNEES OF ONE-HALF TO FREYDBERG BROS. INC., OF NEW YORK, N. Y., A CORPORATION OF NEW YORK

METHOD OF PRODUCING WAISTBAND CURTAINS

Application filed June 24, 1929. Serial No. 373,397.

The invention relates to a method for producing waist band curtains for trousers, skirts and the like as shown and described in our co-pending application, Ser. No. 5 231,370, filed Nov. 5, 1927.

The object of the present invention is the production, by simple and rapid process, of a waist band curtain having its component layers secured together and having a groove 10 adjacent one longitudinal edge thereof.

In order that the method of the present invention may be better understood reference is had to the accompanying drawings, in which:

15 Figure 1 is a diagrammatic view in perspective showing the several steps of the present method;

Fig. 2 is a fragmentary perspective view of a roll of trouser curtain or waist-band made in 20 accordance with the present invention and in the commercial form in which the same is sold ready for attachment to the waist band of garments;

Fig. 3 is an enlarged fragmentary view 25 showing the manner in which the trouser curtain is applied to the garment fabric during the manufacture of a garment;

Fig. 4 is a transverse sectional view taken through the curtain and garment fabric as 30 shown in Fig. 3; and

Fig. 5 is a transverse sectional view through the curtain and garment material and illustrating the position of the same in the finished garment.

35 Referring in detail to the drawings, A indicates the waist-band or curtain which is usually produced in roll form, as indicated in Fig. 2, and B indicates the garment or trousers to which the curtain is attached, as 40 shown in Figs. 3 and 4.

The general construction of the curtain A is substantially the same as those generally used and employed, consisting of a strip of canvas 10 or other stiffening material and a 45 co-extensive strip of twilled or lining fabric 11. It is the usual practice to stitch one edge of the lining, as at 12, longitudinally to the canvas at a point adjacent one edge and in folding the lining around said edge 50 of the canvas, as shown clearly in Figs. 2

and 3, with the major portion of the lining lying in opposed relation to the adjacent face of the canvas strip. While the present disclosure shows the lining and canvas attached as above mentioned, this is not essential and 55 no part of the invention, because it is to be understood that the lining and canvas may be associated in another or any desired manner.

In curtains of the above character, it is 60 found that by adhering the opposing face of the lining to the opposing face of the canvas substantially throughout their areas, such as by pasting or the like that the lining will 65 present at all times a smooth surface which will not pucker nor bulge nor crease with respect to the canvas when being applied by the operator. Aside from the neat appearance presented, this construction admits of quicker production by greatly facilitating the 70 attachment of the curtain to the garment because of the fact that the lining will not bulge or gather which requires the operator to interrupt the attaching operation to straighten out, and, in some cases, to rip the 75 stitching, in order to remove the bulges and gathers. The lining and the stiffening material are adhered together by pasting with an adhesive and to this end the adhesive or sizing usually carried by the stiffening member is utilized.

An impressed groove 15 is formed in the 80 marginal edge portion 14 of the curtain or waist band at a distance inwardly of said edge, say from one-quarter to three-eights of an inch from said edge, this groove forming 85 an effective and inexpensive means on the curtain acting as a stitching guide and a readily bendable line of fold greatly facilitating the application of the curtain and the 90 folding of the same along an even line, which will produce a full rounded appearance at the line of fold in the finished garment.

The curtain above described is made in accordance with the present method by leading 95 the waist band A from a suitable source of supply, such for instance as a roll *a* to a steam jet 17 where the steam is directed upon the waist band so as to moisten or make plastic the sizing or adhesive in the canvas or stiff- 100

ening material 10 of the waist band. The jet of steam is preferably directed against the face of the canvas which opposes the lining layer 11 and, in order to more satisfactorily accomplish this, the layers 10 and 11 of the curtain are separated by a spreader 18 interposed therebetween at a point in its travel in advance of the steam jet 17. From the steam jet 17 the curtain passes between pressure rollers 19 and 20. The roller 19 is provided with a raised circumferential rib 21 on its periphery and the roller 20 is formed with a corresponding groove 22 to receive the rib 21, the groove being slightly larger than the rib to accommodate the thickness of the fabric material so that it will not be cut.

As the curtain passes between the rollers 19 and 20, the action is such as to cause the adhesive or sizing in the canvas 10 to adhere 20 the opposing faces of the canvas and the lining 11 together, substantially throughout this area. At the same time the cooperating rib and groove on the rollers offset the curtain adjacent one longitudinal edge thereof 25 so as to form a relatively deep and wide groove on its canvas side and a corresponding rib on the lining side.

As before stated, this groove is made in the curtain while the canvas is in a moist state, 30 due to the steaming operation, which renders the materials somewhat pliable and facilitates the formation of said groove. As the curtain becomes dry, the groove becomes permanently set therein and remains for an indefinite period of time. The rollers 19 and 35 20 may be heated if desiring to accelerate drying of the curtain or a blast of hot air 23 may be directed upon the curtain after leaving the rollers.

40 The curtain thus formed is wound in roll form (as shown in Figures 1 and 2), the groove on the canvas side of the curtain fitting over the rib on the lining side of the curtain so that the convolutions of the roll will 45 not slip edge-wise with respect to each other, but remain in a neat useable form at all times.

The groove 15 appears on the outer exposed 50 face of the canvas material and is of considerable width, that is, varying from two to three-sixteenths of an inch, the walls of the groove being preferably concaved or semi-circular. The relatively wide groove permits the operator to more readily follow the same with the attaching stitching 16 without running 55 out of the groove, because even though the line of attaching stitching within the groove is slightly irregular, said relatively wide groove will permit the curtain to bend evenly along the groove and present an even line 60 of fold, although the line of attaching stitching may not be perfectly straight. It is essential that the lining and stiffening material be rendered relatively stationary with respect 65 to each other in the practical use of the groove 15, because if this were not the case the

grooves in the canvas and lining would not register during the application of the curtain to the garment. As already pointed out, the lining material often shifts with respect to the canvas during application and the line 70 of stitching 16 would not penetrate the grooves of both materials.

After the stitching operation shown in Fig. 3, the marginal portion of the curtain is turned upon itself and will readily fold and 75 break along the groove 15 as shown in Figs. 3 and 4 in the manner above described, producing a rounded edge at the line of fold which gives a full neat appearance at the edge of the waist opening of the garment. 80 After this operation, the curtain and trouser are handled in the manner generally in practice in the clothing industry.

From the above it will be clear that a very 85 desirable and economical curtain is provided wherein the lining material is at all times smooth and presents a neat appearance, and which is provided with a very economical means acting as a guide or indicator for the line of attaching stitching and readily bendable line of fold which will produce an even and neat appearance even though the line of attaching stitching is not uniformly straight, but made anywhere between the edge 14 of the curtain and the inner edge α of the groove 90 95 15.

Having thus described our invention, what we claim as new and desire to secure by Letters Patent of the United States is:

1. A method of producing a waist band curtain which includes arranging a strip of facing material and a strip of stiffening material in opposed, face-to-face relation, adhering the opposed surfaces of said strips together with an adhesive material in a moist condition by pressing said strips of material together and offsetting said strips along one longitudinal edge thereof to form a depressed groove therein while said strips are in a moist condition whereby the groove becomes set in the fabric material when in a substantially dry condition.

2. The herein described method of producing trouser waist bands which includes advancing in superposed relation a sized stiffening fabric and a lining fabric, moistening the stiffening fabric to render the sizing "tacky"; then subjecting the advancing strips to pressure while moistened to cause them to adhere throughout their contacting areas and offsetting, while moist, a portion of the stiffener strip to provide a groove in one face thereof and an opposed rib on its other face extending along one longitudinal edge thereof, said groove constituting a visible follow line for the operator when stitching the waist band to the trouser material and an easy bending line of fold.

3. The herein described method of producing trouser waist bands which includes

advancing in superposed relation a sized stiffening fabric and a lining fabric, subjecting the stiffener fabric to action of steam to render the sizing "tacky"; then subjecting the advancing strips to pressure while moistened to cause them to adhere throughout their contacting areas and offsetting, while moist, a portion of the stiffener strip to provide a groove in one face thereof and an opposed rib on its other face extending along one longitudinal edge thereof, said groove constituting a visible follow line for the operator when stitching the waist band to the trouser material and an easy bending line of fold.

In testimony whereof we have hereunto set our hands.

OLIVE K. THOMAS.
JOSEPH D. MALKIN.
